UNITED STATES PATENT OFFICE

2,430,942

DOOR HINGE

Raymond McGiff, New York, N. Y.

Application May 1, 1944, Serial No. 533,454

2 Claims. (Cl. 16—176)

1

This invention relates to new and useful improvements in a door hinge.

More specifically, the invention proposes a construction of a closure characterized by a frame, a door in the frame and hidden hinges connecting the door to the frame.

Still further the invention proposes a closure as aforesaid, in which each of the hidden hinges includes a bearing retainer in the frame, a cylindrical sleeve in the retainer, and ball bearings between the sleeve and retainer.

Still another object of the invention is to provide a closure, as aforesaid, in which the hidden hinges permit the door to be removed from the frame at will, without the use of special tools and without removing any part of the hidden hinges from the door or frame.

Another object of this invention is to provide a hidden hinge, as aforesaid, having as a feature thereof, an adjustable door stop.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary foreshortened vertical sectional view of a closure embodying the present invention, parts being shown in full.

Fig. 2 is a view similar to Fig. 1 of a closure constructed in accordance with a modification of this invention.

Fig. 3 is a view similar to Fig. 1 showing a top hidden hinge constructed in accordance with a modification of this invention, having as a feature thereof, an adjustable door stop.

Fig. 4 is a plan view of the structure of Fig. 3.

The closure shown in Fig. 1 includes a frame 10, a door 11, a top hidden hinge 12 and a bottom hidden hinge 13.

Hinge 12 includes a bearing retainer 14 which is sunk into the frame 10 above one corner portion of door 11. Retainer 14 has a cylindrical base, two spaced horizontal raceways 15 in the wall of the bore, and an annular shoulder 16 extending inwardly from the bottom edge of the bore. A cylindrical sleeve 17, having an axial bore throughout its length, is disposed in retainer 14, and is supported on top of shoulder 16. Ball bearings 18 are disposed in raceways 15 between sleeve 17 and retainer 14. Thus sleeve 17 is free to rotate in retainer 14 and is prevented from dropping out of the retainer by shoulder 16. The

2

inside diameter of the bore of sleeve 17 is similar to the inside diameter of the bore of shoulder 16.

A casing 19 is sunk into door 11 in line with the retainer 14. It has an axial bore 20 open at its outer end at the top of the door 11 and closed at its inner end by a horizontal wall 21. Opposed elongated slots 22 are formed in the side wall of the casing.

A coil spring 23 is disposed in bore 20, seating on wall 21, and a pin 24 is also disposed in bore 20 on top of spring 23. Pin 24 has trunnions 25 which extend into slots 22. When the trunnions are at the top of the slots as shown in Fig. 1, the spring 23 will be under some compression, thereby holding the pin 24 in its full upward position. The trunnions may be formed by a pin forced through a hole in the pin 24. The pin 24 and casing 19 will be associated before the casing 19 is sunk into door 11. A row of recesses 26 are formed in the pin 24 at right angles to the trunnions 25 and in the portion of the pin adapted to extend above the casing 19.

These recesses may be formed by drilling into the pin 24. They are for employment in removing the door from the frame. This may be accomplished by swinging the door at right angles to its position shown in Fig. 1, inserting a pointed tool such as an awl between the top of the door and the adjacent part of the frame and into a recess 26, moving the pin 24 downward until another awl can be inserted into another recess and so on until the pin 24 is entirely out of sleeve 17 and retainer 14. The top of the door may then be pulled out of the frame and the door lifted, as will presently appear, to disconnect the bottom hinge and thereby completely remove the door from the frame.

The bottom hinge 13 includes a bearing retainer 27 having a vertical cylindrical bore 28 open at its top and closed at its bottom by a wall 29. Two horizontal spaced raceways 30 are formed in the cylindrical wall of the bore. A thrust bearing 31 is disposed in the bottom of the bore 28. A hollow cylindrical sleeve 32 having an axial bore open at its top end and closed at the bottom by a wall 33 is disposed in the bearing retainer 27 with its wall 33 seating on top of the thrust bearing 31. Ball bearings 34 are disposed in raceways 30 between sleeve 32 and retainer 27. If desired a retainer identical to retainer 14 may be used, thrust bearing 31 being supported by shoulder 16. Further, a sleeve identical with sleeve 17 may be used,

the bottom edge of sleeve 17 seating on the thrust bearing.

A casing 35 is sunk in the bottom of door 11. It has a cylindrical bore 36 open adjacent the bottom of the door 11 and closed at its other end by a wall 37. A pin 38 removably connects casing 35 with retainer 27. It has a cylindrical portion 39 disposed in bore 36 with its top end in engagement with wall 37, a reduced portion 40 is disposed in the sleeve 32 and a shoulder 41 between portions 39 and 40 in engagement with the top edge of sleeve 32.

It is contemplated that there will be enough lateral play between the parts of the hinge 13 to permit the top of the door to be moved out of the frame. The door may then be simply lifted so that casing 35 comes away from pin 38, pin 38 staying with retainer 27. If desired, means may be provided (not shown) so that pin 38 will stay with casing 35 and leave retainer 27 when the door is lifted. For instance a casing identical to casing 19 may be employed and the pin 38 may be provided with trunnions for sliding movement in the slots of the casing.

From the above description it will be apparent that the hidden hinges 12 and 13 provide a simple means for hinging a door to its frame in such a manner that the door may readily be taken out of its frame without the removal from the door and frame of any parts of the hinge.

In the modification of the invention shown in Fig. 2, the construction of the top hinge 42 is similar to the hinge 12 except for the portion of the top hinge sunk in the frame. Parts of hinge 42 similar to corresponding parts of hinge 12 will be indicated by like reference numerals with a prime mark or an accent added, and as to like parts no further description thereof is deemed necessary.

The retainer 43 of hinge 42 is sunk in frame 10 and has a cylindrical bore 44 and an annular shoulder 45 extending inwardly from the bottom of the bore 44. A raceway 46 is formed in the shoulder 45 and ball bearings 47 are disposed therein forming an end thrust or support bearing. A sleeve 48 having an axial bore 49 and a horizontal raceway 50 in its outer face is disposed in bore 44 with its bottom edge supported on the ball bearings 47. Ball bearings 51 are disposed in raceway 50 between sleeve 48 and retainer 43. The bottom hinge for the door 11' is identical with the hinge 13.

The operation of this form of device is similar to the closure shown in Fig. 1. While the retainers have been shown disposed in the frame, the hinges may be reversed if desired and the retainers disposed in the door.

In the modification of the invention shown in Figs. 3-4, the construction of the hinge is similar to the hinge shown in Fig. 1 but distinguishes therefrom as follows:

A pin 52 having serrations 53 in its upper end is provided, the serrations mating with serrations 54 formed in the bore of a sleeve 55 disposed in a bearing retainer 56. The top edge of the retainer 56 is provided with shoulders 57 and 58 and sleeve 55 has a finger 59 overriding the lowermost portion of the top edge of retainer 56 and adapted to abut shoulders 57 and 58 respectively depending upon the direction in which the door is opened. Other parts of the closure of Figs. 3 and 4 similar to corresponding parts of the closure of Fig. 1 are indicated by like reference numerals with two accents added.

Finger 59 is shown in the drawing disposed 75

midway between shoulders 57 and 58, thus allowing the door to swing an equal amount in either direction. Shoulders 57 and 58 limit the swing of the door and will stop it in a predetermined position. This is desirable in doors having hidden hinges because the door is disposed midway in the frame and if it is swung too far in either direction it will hit the frame and will tend to rip the hinges out of the door.

10 The position of finger 59 may be adjusted, if desired, to change the amount that the door may be swung. This is of value, for instance, where it is contemplated that the door will only be swung in one direction, from its position in the frame. To make this adjustment, the pin 52 can be assembled with the sleeve 55 with the finger 59 disposed at any desired angle relative to the trunnions 25" of the pin. The serrations 53 and 54 provide a simple means of accomplishing this adjustment.

15 The maximum angle that the door may swing through will normally be less than 180 degrees due to the fact that the door is disposed in the frame. As the angle between the shoulders 57 and 58 is greater than 180 degrees, it is therefore possible to obtain a maximum swing in either direction.

20 While I have illustrated and described the preferred embodiments of my invention, it is to be understood that I do not limit myself to the precise constructions herein disclosed and the right is reserved to all changes and modifications coming within the scope of the invention as defined in the appended claims.

25 Having thus described my invention, what I claim as new, and desire to secure by United States Letters Patent is:

30 1. A hinge mounting for supporting a door in a frame comprising a hidden hinge at the top of said door pivotally connecting said door to said frame, said hinge including a sleeve retainer in said frame, a sleeve in said retainer adapted to rotate therein, said sleeve and retainer having coacting parts limiting the extent of rotation, and a pin having a portion keyed in said door and another portion keyed in said sleeve for rotation therewith, whereby said sleeve limits the angle of swing of said door.

35 2. A hinge mounting for supporting a door in a frame comprising a hidden hinge at the top of said door pivotally connecting said door to said frame, said hinge including a bearing retainer in said frame having two spaced shoulders in its top edge, a hollow sleeve in said retainer having a bore provided with serrations and having a finger extending and riding said top edge between and adapted to coat with said shoulders, ball bearings between said retainer and sleeve, a cylindrical casing in said door having an axial bore open at its end adjacent the top of said door and closed at its opposite end, opposed slots in the side walls of said bore extending axially thereof, a pivot pin in said bore having trunnions disposed in said slots for movement of said pin axially of said bore, and a spring disposed in said bore between said closed end and the adjacent end of said pin, urging said pin through said open end, said pin being serrated at its upper end portion, said trunnions limiting the extent of said movement away from said closed end, said pin, when extended through said open end, being disposed in said sleeve with its serrations mating with the serrations of said sleeve for pivotally connecting said door at its top to said frame, said pin being adapted to be disposed entirely in said

bore, thereby adapting said door at said top thereof to be moved out of said frame, said finger and shoulders coacting to limit the swing of said door.
